CLAIM

I claim the ornamental design for a combination funnel and water filter, as shown and described.

DESCRIPTION

FIG. 1 is a top, front and side elevation perspective view of the combination funnel and water filter in place on top of one type of liquids container;

FIG. 2 is a top, front and side elevation perspective view of the combination funnel and water filter in place on top of another type of liquids container;

FIG. 3 is a top plan view of the combination funnel and water filter;

FIG. 4 is a left side elevation view of the combination funnel and water filter;

FIG. 5 is a front view of the combination funnel and water filter;

FIG. 6 is a bottom view of the combination funnel and water filter;

FIG. 7 is a right side elevation view of the combination funnel and water filter; and,

FIG. 8 is a rear view of the combination funnel and water filter.

The broken line showing of environment in FIG. 1 and FIG. 2 is included for the purpose of illustration only and forms no part of the claimed design.
